Lauterbur, deceased

Application March 28, 1929, Serial No. 350,765

8 Claims. (Cl. 110—101)

Our invention relates to furnaces, especially those for heating plants in domestic establishments.

While the art of automatic furnace stoking and control has been extensively developed, the equipment heretofore made has been particularly for use with large heating plants such as are required for the boilers of factories, and there are many conditions in a domestic heating plant 10 which require apparatus of different types, and controls therefor operable on different principles.

We have, at the outset, the broad idea of an automatic furnace which does not require the services of an attendant, and which, therefore, 15 may be installed in homes where the owners are not necessarily possessed of engineering ability.

Most automatic stoking equipment has been designed with controlling apparatus based on the heat produced in the furnace, but, while my preferred control has an auxiliary incidental control based on a thermal element positioned so as to become effective with variations of temperature near the lower limit line of the fuel in the furnace, it is broadly the object of our invention to 20 provide a volume control which regulates the supply of fuel to the fire in accordance with the volume of fuel within the furnace. It is one of our objects, in one preferred arrangement, to provide a fan for forced draft which is controlled by a 25 thermal element located near the grate line so that when the level of fuel is low and there is danger of burning or melting the grates, the air blast is automatically shut off. This may be provided in several different ways; in one system by 30 driving the fan with a clutch from the stoker motor controlled by the thermal element near the furnace grate lines.

The problem of feeding fuel to a furnace from an underfeed conveyor has been greatly complicated in previous installations by provision of conveyors having the greatest tendency to block at positions removed from the source of power. In order to avoid such a tendency to block, it is one of our objects to provide a conveyor in which 45 the greatest tendency to block is located close to the source of power so that the greatest strain on the apparatus occurs where the power is greatest, and once having passed the position of greatest strain the fuel flows readily through a 50 conduit which flares out, and thus provides a less restricted passage the farther the fuel is moved away from the driving end of the apparatus.

It is another object of our invention to provide a volume control which may be adjustable for 55 different seasons, so that while in the coldest

weather conditions may be such that a heavy bed of fuel is required, in warmer weather a lighter bed may suffice.

In order to simplify the removal of ashes from the furnace, it is our object to provide an ash conveyor operated by the same power which drives the feeding device. In combination with such a conveyor, it is an object of our invention to provide a depressed container for receiving the ashes from the conveyor.

While we provide controls for automatically regulating the burning of the fire, separate and distinct from the ordinary house thermostat control, it is within the contemplation of our invention to regulate the drafts for the furnace from a house thermostat which not only may augment the nicety of the regular controls, but which may be so arranged to regulate the path of the oxidizing air currents through the fire bed.

The above and other objects to which reference will be made in the ensuing disclosure we accomplish by that certain combination and arrangement of parts of which we have shown several preferred modifications.

Referring to the drawings:

Figure 1 is a side elevation of one arrangement of furnace and stoking apparatus.

Figure 2 is a front elevation of the arrangement shown in Figure 1.

Figure 3 is a side elevation of the combination shown in Figures 1 and 2 with parts broken away and in section revealing the internal structure.

Figure 4 is a horizontal cross section through the furnace and stoker along the line 4—4 in Figure 2.

Figure 5 is a detail view with parts in section which would correspond with Figure 3, but showing a different arrangement for volume control.

The furnace illustrated is of the ordinary hot air type, having an exterior shell 1 and a fire pot 2. The grate bars which support the bed of coals are indicated at 3, and in the center of the grate we have shown the discharge portion 4a of the fuel supply conduit which, as will be noted, is of flaring shape thereby offering less and less resistance to the fuel as it passes from the intake end 4 of the conduit to the discharge portion 4a, which opens upwardly a considerable distance above the grate, and from which the fuel ordinarily tumbles over onto the grate bars, or 100 bed of coals supported thereon.

The feed conveyor is of novel type, having a shaft 5, which carries worm sections 6 and narrower sharper breaker bars 7. The drive for the feed screw is best illustrated in Figure 2. An 110

electric motor 8 is provided, which has a pinion 9 which engages and drives a gear 10 mounted on a shaft 11. The shaft 11 carries a worm 12 which engages a worm gear 13 mounted on the 5 shaft 5. A clutch 14 is arranged with a lever acted upon by a magnet 15 which throws the clutch in and out, and the fan 16 may thus be driven in response to the electromagnetic control. The shaker bar 17 shown in Figs. 1 and 4 10 connects to slide 17a, which by pitman 17b connects to gear 17c meshing with pinion 17d on the shaft of the fan 16, so that the grate is shaken only when the fan runs.

Referring to Figure 3 a bevel pinion 18 mounted 15 on the screw shaft 5 engages a bevel gear 19. The gear 19 is mounted on a vertical shaft 20 which carries a large sprocket wheel 21, which drives the ash drag link conveyor 22. The discharge from the ash conveyor is a chute 23 which 20 discharges into an ash can 24 seated within a pit 25 in the furnace room floor.

The fuel hopper is indicated at 26 and as shown in Figure 1 it will preferably be provided with a crusher bar 27, which may be suitably 25 driven from the train of gears driving the feeding screw.

The volume control is provided in the combination shown in Figures 1 to 4 by a spreading member 28 located in the path of fuel from the feed 30 hopper. The member 28 is mounted on a rod 29 which extends up through a sleeve 30 with a member 29' at its top by which a switch 31, connected to motor 8 by wires 31a and 31b (Fig. 2) may be actuated by the elevation of the rod, 35 thereby opening the circuit to stop the motor 8 at maximum fuel height, or closing the circuit to start the motor at minimum fuel height.

The furnace may, as indicated in Figure 3 have a casing header 32 with draft dampers 33 associated therewith, which may be controlled by a 40 house thermostat, but since the controls for such dampers are ordinarily well known in the art no further reference will be made to any preferred type of thermostatic control. The thermostat 34 is located near the horizontal plane of the 45 grate as shown in Fig. 3, and has its two elements held together, closing a circuit through the magnet 15 by way of the wires 34a and 34b as seen in Fig. 2, so that the magnet 15 acts through the 50 lever as before described to hold the clutch 14 in engagement for operating the fan 16, unless the temperature near the grate line, due to fall of the fire level, drops below a certain minimum, upon which the thermostat elements separate, 55 breaking the circuit so that the clutch 14 is no longer held in engagement, and the fan is stopped. This prevents blowing the fire when it is so low that the grate and other parts might be injured thereby. As the grate shaker 17 is 60 operated only when this clutch 14 is engaged, the fire is not shaken when it is so low that it might be extinguished by shaking. The rate of burning depends, in addition to the nature of the fuel, upon the amount of blowing and shaking. The 65 amount of shaking influences the height of fuel bed, which influences the rate of falling of fuel from the supply over inlet 4a to the fire bed, which blocks this fall of fuel more or less as it is higher or lower.

In Figure 5 the spreader member 28a is carried on a rod 29a, which extends down through sleeves 30a to actuate a switch 31a, which in a manner similar to the operation of the switch 31 of the other example, controls the operation 75 of the motor driving the automatic stoker. The

member 29' that operates the switch 31 is adjusted up or down on the rod 29 connected to the element 28 in the fuel inlet 4a, according to weather conditions. The higher the member 29' is adjusted, the less will be the accumulation of fuel above inlet 4a, and the less will be the fall of fuel to the fire bed, with consequent decrease in fire bed, and greater tendency to stop the fan and the ash shaker, which will result in slower burning. The ash removal from the pit will be proportional to the fuel supply, since the ash conveyor 22 is operated only as long as the fuel supply conveyor operates. It will be seen therefore that the single adjustment of the member 29', or the corresponding member of the element 28a in Fig. 5, adjusts the operation of all of the devices. When this member is adjusted lower, the fuel accumulation at inlet 4a is increased, with more fall of fuel to the fire bed, increase of depth of fire bed, and more continuous operation of the blower and ash shaker, and consequent faster burning. The rate of removal of ashes will proportionately increase. As element 28 or 28a is in fuel that is not burning, and protected by a considerable volume of this fuel all 100 around it between it and the fire bed, this element is subjected to but little destructive influence, and its operative connection also is far removed from the fire bed, in either example.

While we have not gone into great detail in 105 describing or illustrating the several modifications of our apparatus disclosed herein, it will be apparent that a wide range of structural changes will occur to those skilled in the art without departing from the principle of our invention.

Having thus described our invention what we claim as new and desire to secure by Letters Patent, is:—

1. In an automatic furnace comprising a firepot and a fuel supporting surface, a mechanical stoker including a fuel supply conduit entering said furnace below said surface and discharging above said surface, a fan having a discharge outlet under said surface, mechanism for forcing fuel in through said conduit, means for operating said mechanism and said fan together comprising a disconnectible operative connection between said operating means and the fan, thermally operated control means near said fuel supporting surface, and a connection from said thermally operated control means to said disconnectible operative connection whereby the fan is disconnected from the operating means or connected thereto according to temperature conditions near said surface independently of the operation of said mechanism.

2. In an automatic furnace comprising a firepot and a fuel supporting surface, a mechanical stoker including a fuel supply conduit entering said furnace below said surface and having a discharge portion extending a material distance above said surface, an element adjacent to said discharge portion raised or lowered in response to increased or diminished accumulation of fuel above said discharge portion, mechanism for forcing fuel in through said conduit, operative connecting means whereby the raising or lowering of said element stops or starts said mechanism, a fan discharging into said furnace below said surface, a disconnectible operative connection between said fan and said mechanism, thermally operated control means near said fuel supporting surface, and a connection from said control means to said disconnectible operative connection whereby the fan is disconnected from said 145

mechanism or connected thereto according to temperature conditions near said surface independently of the operation of said mechanism.

3. In an automatic furnace comprising a firepot and a fuel supporting surface, a fuel feed conduit entering said furnace below said surface and having its delivery outlet a material distance above said surface, a spreader member above said outlet adapted to spread the fuel coming from

10 the outlet outward and downward onto said surface and to be raised or lowered in response to increased or diminished accumulation of fuel above said outlet, mechanism for forcing fuel in through said conduit and operative connecting means whereby the raising or lowering of said spreader member stops or starts said operating mechanism.

4. In an automatic furnace comprising a firepot and a fuel supporting surface, a fuel feed conduit, 20 an air inlet, and an ash chute extending into the furnace under the fuel supporting surface, the conduit having a discharge portion extending a material distance above said surface, conveying means in the chute and conduit, respectively, operating mechanism common to both conveying means, a fan discharging into said air inlet, disconnectible means operatively connecting said fan with said operating mechanism, thermally operated control means near said fuel supporting 25 surface, a connection from said control means to said disconnectible means whereby the fan is disconnected from the operating mechanism, or connected thereto, according to temperature conditions near said surface, a motor driving said mechanism, an element disposed at the outlet of the fuel feed conduit discharge portion, raised or lowered in response to increased or diminished accumulation of fuel at said outlet, and means controlling the operation of said motor and operably related to said element whereby the motor is stopped in response to the rise and started in response to lowering of said element.

5. In an automatic furnace comprising a firepot and a fuel supporting surface, a fuel feed conduit, an air inlet, a fan discharging into said air inlet, and an ash chute extending into the furnace under the fuel supporting surface, the conduit having a discharge portion extending a material distance above said surface, said surface comprising a shakable grate around said discharge portion, an operative connection from said fan to said grate whereby said grate is shaken when said fan is operating, conveying means in the chute and conduit, respectively, operating mechanism common to both conveying means, disconnectible means operatively connecting said fan with said operating mechanism, thermally operated control means near said fuel supporting surface, a connection from said control means to said disconnectible means whereby the fan is disconnected from the operating mechanism, or connected thereto, according to temperature conditions near said surface, a motor driving said mechanism, an element disposed at the outlet of the fuel feed conduit discharge por-

tion, raised or lowered in response to increased or diminished accumulation of fuel at said outlet, and means controlling the operation of said motor and operably related to said element whereby the motor is stopped in response to the rise and started in response to lowering of said element.

6. An automatic furnace comprising a fuel-supply conduit having an outlet opening upwardly therein and a grate alongside of said outlet, spaced downwardly from the outlet such a distance as to support a fire bed in controlling relation to the fall of fuel from said outlet to said fire bed, a conveyor forcing fuel through said outlet, means forcing air to said fire bed, control means adjacent to said outlet, raised and lowered in response to increased and diminished accumulation of fuel in said outlet, means whereby said conveyor is started and stopped in response to lowering or raising of said control means, and controlling means adjacent to said fire bed, stopping and starting said air forcing means in response to decrease and increase in heat emanating from said fire bed.

7. An automatic furnace comprising a fuel-supply conduit having an outlet opening upwardly therein and a grate alongside of said outlet, spaced downwardly from the outlet such a distance as to support a fire bed in controlling relation to the fall of fuel from said outlet to said fire bed, a conveyor forcing fuel through said outlet, means for forcing air to said fire bed, control means adjacent to said outlet, raised and lowered in response to increased and diminished accumulation of fuel in said outlet, means whereby the conveyor is started and stopped in response to lowering and raising of said control means, and thermostatic control means for said air forcing means, near the level of said grate, starting and stopping said air forcing means in response to increase and decrease in heat emanating from said fire bed.

8. An automatic furnace comprising a fuel-supply conduit having an outlet opening upwardly therein and a grate alongside said outlet, spaced downwardly from the outlet such a distance as to support a fire bed in controlling relation to the fall of fuel from said outlet to said fire bed, a conveyor forcing fuel through said outlet, means for forcing air to said fire bed, means for shaking ashes from said fire bed, said air-forcing means and said ash-shaking means being operatively connected for simultaneous operation, control means adjacent to said outlet, raised and lowered in response to increased and diminished accumulation of fuel in said outlet, means whereby said conveyor is started and stopped in response to lowering and raising of said control means, and controlling means adjacent to said fire bed, starting and stopping said air-forcing means and said ash-shaking means in response to increase and decrease in heat emanating from said fire bed.

FRANK X. LAUTERBUR.
EDWARD J. LAUTERBUR. 140
